TREATMENT OF HIGH TEMPERATURE
COAL TARJacquelin E. Harvey, Jr., Atlanta, Ga., assignor
of one-half to Southern Wood Preserving Com-
pany, East Point, Ga., a corporation of Georgia

Application June 20, 1940, Serial No. 341,595

2 Claims. (Cl. 196-53)

The present invention relates to the joint production of useful products, and more specifically relates to the joint production of useful products from high boiling fractions of tar, including pitches and the so-called residual tar.

An object of the invention is the joint production of wood preservatives and solvents from high boiling fractions of tar, including pitch, and constitutes an improvement on Patent 2,082,885, granted to me on June 8, 1937.

Other objects of the invention will become apparent from following disclosures.

Patent 2,082,885 describes a method for the production of wood preservatives from pitch to the end that said pitch, substantially in its entirety, is converted into a wood preservative of enhanced value and controllable specifications, as for instance those specifications meeting A. W. P. A. requirements. Such a process made available to creosote manufacturers a method whereby coal tar, or the like, could be converted substantially in its entirety, as for instance 80% or better, into wood preservatives, with the added benefit that said process eliminated the final production of pitch incidental and inherent to wood preservative (creosote) production from coal tar or the like by conventional distillation or extraction methods.

It is well known in the industry that this country has for years imported millions of gallons of creosote from abroad even though the raw parent material of creosote—coal tar or the like—was and is domestically produced in such quantities as to make available by conventional distillation methods an amount of creosote to provide national sufficiency. However, this country did not take advantage of the adequate raw material supply—coal tar or the like—to the end that national sufficiency in creosote be realized, for the reason that distillation recovery of creosote from tar resulted in the production of in the order of 50% pitch which was at times a distress product.

The process described in Patent 2,082,885 provides, as aforesaid, a method for substantially total conversion of coal tar, or the like, into refined wood preservatives by, first, distilling said tar for creosote recovery and, second, the conversion of the resultant pitch by the action of hydrogen, substantially in entirety, into refined wood preservative. Thus a method was provided for substantially volume for volume conversion of refined wood preservative from coal tar, or the like.

With such a process available, smaller quan-

tities of coal tar, or the like, would be required to the end that national sufficiency in refined wood preservatives, as for instance creosote or creosote-coal tar solutions or their modifications, be secured. With an average annual coal tar production of 500-600 million gallons and an annual average consumption of refined tar wood preservatives of 200 million gallons, and employing the process of U. S. Patent No. 2,082,885, it is apparent that 300-400 million gallons of tar would be available for other purposes.

It is now found that instead of converting pitch, substantially in entirety, to wood preservatives as described in Patent No. 2,082,885, pitch may be converted, substantially in entirety, jointly into solvents of superior quality and wood preservatives of enhanced toxic value.

By describing the solvents of the present invention as being of superior solvency is meant that said solvents are in the order of approximately 50% aromatic, or more, and as is well known in the art can only be accomplished by precluding excessive destruction of the aromatic nuclei in the starting material. When assigning to the wood preservatives of the present invention an enhanced toxic value, is meant that the toxicity of said wood preservatives is in excess of the toxicity of said starting material and thus, as is also well known in the art, cannot be provided if excessive rupture of destruction of the aromatic nuclei in the starting material take place.

The present invention to the end that the starting materials of the process be converted substantially entirely to said solvents and wood preservatives, insofar as applicant understands same, is predicated on:

First, that the molecular complexes of the starting material, as hereinafter explained, are converted in step wise manner to produce the products and/or product of the present invention.

Second, that the reduction including in size, of said molecular complexes be accomplished under a partial pressure of at least a fractional atmosphere of hydrogen sulfide.

The invention will be understood from the following description of illustrative steps comprising various methods of securing the objects of the invention, when read in connection with the accompanying drawing wherein the figure is a diagrammatic sketch of an apparatus for carrying out a form of the process of the invention and wherein the nature of the step carried out

in each chamber and the contents thereof are indicated by legend.

Example 1.—A tar pitch boiling substantially 15% at 355° C. was subjected to the action of hydrogen in a continuous manner in a high pressure reaction chamber, under the influence of a molybdenum sulfide catalyst, at 400° C. and 300 atmospheres pressure. Time of contact was 2 hours. Inspection of the beneficiated product during the first portion of the run showed a yield of 10% distilling to 205° C. and approximately 22% distilling from 205° C. to 355° C.

The product recovered up to 205° C. was the solvent of the present invention and boiled predominantly between 165° C.—205° C. and had an aromaticity of in the order of 50%; the product boiling substantially between 205—355° C. was the wood preservative of the present invention and had a toxicity comparable to conventional creosote, and a toxicity in excess of its parent material. As is usually recognized the pitches have little or no toxicity. The residue incidental to the recovery of said wood preservative may be used as an article of commerce or recycled, with or without addition of other starting material for compensation for diminution in volume incidental to product recovery.

At the end of the 36th hour of the use of the catalyst, the conversion of the starting pitch to products of the present invention was reduced. Research disclosed that the cause of such reduction was due to failure of the catalyst to be maintained in substantial sulfide form, that is to say, the catalyst appeared to be converted to other form, at least to a degree. By adding 1/2 of 1% sulfur to the starting material (pitch), it was found that substantially the initial high rate of reaction was established, and continued substantially so thereafter.

Thus, the initiating and continuance without substantial reduction, other than that incidental to catalyst age, of reaction conditions that produce the solvents and wood preservatives of the present invention are predicated on the maintenance of a hydrogen sulfide partial pressure of at least a fractional atmosphere. At times the partial pressure of hydrogen sulfide may be as high as one atmosphere, or higher. The partial pressure of hydrogen sulfide of the present invention, is that partial pressure required to maintain the sulfide catalyst in substantial sulfide form.

Some starting materials of the present process may have sufficient sulphur therein contained to supply the needs incidental to the sulfide catalyst being maintained in substantial sulfide form. Other starting feeds may require the addition of sulphur. The amount of sulphur necessary to maintain the sulfide catalyst in substantial sulfide form will readily be found after a few trials, and in the event of sulphur deficiency, the same is added.

Viewed broadly, the present invention provides a process for the conversion of a high boiling fraction of tar into solvents of superior solvency and wood preservatives of enhanced toxic value, wherein said high boiling tar fraction is subjected to the action of hydrogen and hydrogen sulphide, in the presence of a sulfide catalyst, whereby said tar high boiling fraction, substantially in entirety is converted in step-wise manner to the solvents and wood preservatives as aforementioned. It can be explained that the action of sulfur in the instant process also has the unexpected effect of reducing the toxicity

blanketing effect of the residual above 270° C. in the wood preservative produced, as compared to a product produced by a similar process without sulfur. It is recognized in the art that the toxicity of a tar derived wood preservative is proportional to the percentage distilling below 270° C. However, it is also recognized in the art that the residual above 270° C. in the wood preserving oil lowers or has a toxicity blanketing effect on the overall wood preservative. The inclusion of hydrogen sulfide in the instant process reduces the well known toxicity blanketing effect in the residual above 270° C. in the wood preserving oil.

Example 2.—Various methods of practicing the present process are possible, as will immediately become apparent to those skilled in the art.

For instance, the pitch of Example 1 may be treated in the first cycle for the recovery of the solvents and wood preservatives of the present invention, thereafter recycling the residue, with or without the addition of added starting material, for conversion only to wood preservative.

Example 3.—The present process is also adapted to convert specific high boiling fractions of tar into the solvents and wood preservatives of the present invention, as for instance wax oil and high residue recovered from high residue creosote; also selected high fractions, including pitch, from "petroleum aromatics".

High residue recovered from high-residue creosote, said high residue boiling substantially 97% above 380° C. and having a coke residue in excess of 4% was adjusted to sulphur content by adding an amount of sulphur thereto that under process conditions gave at least a partial atmosphere hydrogen sulfide partial pressure. Said high-residue was charged to a high pressure bomb and charged with hydrogen to 2000 lbs. Heat was then applied to an upper limit of 410° C., meanwhile agitating the bomb. The run continued 8 hours. At the end of said 8 hour period the bomb was allowed to cool and recharged with fresh hydrogen to 2000 lbs. Identical reaction controls were reinstated and the run continued for an additional 8 hours. At the end of said period the beneficiated material was withdrawn from the bomb, dissolved and occluded gas removed, and distilled for solvent and wood preservative recovery. The distillation cut was made at 200° C., with the distillate serving as the solvent of the present invention and the residue as wood preservative. The solvent boiled predominantly between 50° C. and 200° C. and had an aromaticity of in the order of 50%. The wood preservative had a coke residue within wood preservative specification limits, a toxicity in excess of its parent material and a permissible initial boiling point in view of specifications extant.

As noted in the foregoing, the beneficiated material flowing from the process controls of the present invention may be fractionated to produce (a) the solvent as a distillate and the residue thereof as a wood preservative or (b) the solvent and wood preservatives as distillates with the residue resulting therefrom used as an article of commerce or recycled.

The starting materials of the present process are high boiling fractions of aromatic tars and tars of aromatic content, including pitches, acid or neutral, crude or refined, as for instance one or more times refined by hydrogen.

Also suitable starting materials of the present process are residual tars, by which is meant tars

from which have been removed certain high boiling solvents.

The term liquid phase as used herein and in the appended claims is used to differentiate from the gas phase which gasifies substantially all or substantially the entirety of the feed material. The term liquid phase may not be technically correct, inasmuch as a certain portion does exist in vapor phase, however, as used herein, the liquid phase predominates.

The process is also adapted to be practiced in continuous or intermittent operation; reaction chambers may consist of a simple chamber, a multiplicity thereof, in series or parallel.

All sulfide hydrogenating catalysts are usable, as for instance those of the 6th periodic group; especially effective are the sulfides of vanadium, tungsten, tin, molybdenum and uranium; sulfide catalysts in admixture with other materials possessing hydrogenating qualities or not; deposited on carriers, extruded, in various shapes, comminuted or in proper form to aid surface contact; promoted or not; with halogen derivatives or not; all hydrogenating catalysts of sulfide form.

As is well known, hydrogenations proceed at only slightly elevated temperatures and pressures; however, elevated temperatures are desirable, and the preferred pressure is 200-400 atmospheres. However, pressures as high as 1000 atmospheres or higher are usable. Temperatures chosen between 200° C. and 650° C. are the practicable process limits, however, good operation may be had between 375° C. and 425° C.

The point of fractionation between the solvent and the wood preservative is flexible. As an example, commercial solvents are of varying boiling ranges and end points, and by a like token, commercially acceptable wood preservatives are of varying initial boiling points; thus inasmuch as in the present invention, the end point of the solvent approximates the initial boiling point of the wood preservative, the distillation cut may be at various points. Some commercial solvents on the market have the following end points:

Commercial solvent:

	End point, °C.
Benzol	120
Toluol	150
High-flash naphtha	200
Heavy naphthas	above 200

Some commercial wood preservatives on the market have the following initial boiling points:

Commercial wood preservative:

	I. B. P.
American Wood Preservers' Association	5% at 210° C.
American Wood Preservers' Association	1% at 210° C.
American Wood Preservers' Association	1 1/2% at 235° C.
Prussian Ry	3% at 150° C.
Neville Shingle Stain Oil	150° C.
Southern Pine Shingle Stain Oil	92° C.

Thus, from the foregoing it will be seen that there is no inflexible point at which the solvent and wood preservative must be separated; further, it will be strictly understood that the foregoing solvent end points and wood preservative initial boiling points are illustrative only, and that the cut may be made at any point as determined by manufacturing necessities.

Also, when recovering the wood preservative as a distillate, the end point may be at any desired point consistent with consumer acceptance. Accepted and specification wood preservatives seldom limit end point. Thus, the present invention may be applied to produce the wood preservative as a distillate whose end point is that end point desired. In the following are listed several accepted wood preservatives having no limitation on end point.

WOOD PRESERVING IMPREGNANTS

Specification

1. American Wood Preservers' Association:
  - a. Up to 210° C., not more than 5%.
  - b. Up to 235° C., not more than 25%.
2. American Wood Preservers' Association:
  - a. Up to 210° C., not more than 1%.
  - b. Up to 235° C., not more than 10%.
  - c. Up to 355° C., not less than 65%.
3. American Wood Preservers' Association:
  - a. Up to 235° C., not more than 1 1/2%.
  - b. Up to 300° C., not more than 16 1/2%.
  - c. Up to 355° C., not less than 45%.
4. American Wood Preservers' Association:
  - a. Up to 210° C., not more than 8%.
  - b. Up to 235° C., not more than 35%.
5. American Wood Preservers' Association:
  - a. Up to 210° C., not more than 10%.
  - b. Up to 235° C., not more than 40%.
- 35 6. American Wood Preservers' Association:
  - a. Up to 210° C., not more than 5%.
  - b. Up to 235° C., not more than 15%.
7. Prussian Ry.:
  - a. Up to 150° C., not more than 3%.
  - b. Up to 200° C., not more than 10%.
  - c. Up to 235° C., not more than 25%.
- 45 8. National Paint, Varnish & Lacquer Association:
  - a. 5% at 162° C.
  - b. 97% at 270° C.
9. Southern Pine Shingle Stain Oil:
  - a. 5% at 137° C.
  - b. 95% at 257° C.
- 50 10. Neville Shingle Stain Oil:
  - a. I. B. P., 150° C.
  - b. 5% at 205° C.
  - c. 95% at 292° C.

Thus, from the foregoing it will be seen that the listed specifications place no arbitrary end point on the wood preservatives; generally, the end point is determined by customer preference.

Summarizing: The present invention provides a process for the conversion of high boiling fractions of tar, including pitch, into solvents and wood preservatives of superior solvency and enhanced toxic value, said solvents and wood preservatives being characterized as being substantially total conversion products of said high boiling fractions, and being further characterized in that said conversion was effected under the influence of hydrogen and a hydrogen sulfide partial pressure of at least a partial atmosphere while in the presence of a sulfide catalyst.

Pitches and high boiling tar fractions at least once refined by hydrogen are especially adapted as starting materials of the present process.

Solvents may be used to reduce carbon concentration in any of the starting materials prior to treatment by the process of the present invention.

By the term beneficiated as used herein and in the appended claims, is meant the starting material at least once subjected to the process controls of the present invention. The high boiling materials may be passed through a reaction chamber under conditions that refine but fail to produce the products of the present invention in a commercial manner; thereafter the refined material may be subjected to process controls that produce the products of the present invention.

The solvents of the present invention vary in their lower boiling range in accordance with impressed controls; controls may be impressed to provide solvents boiling as low as 50° C., or lower. The overall solvents so produced may be fractionated to provide various cuts.

When processing high boiling fractions of relatively high carbon content, or others, impressed process conditions may be less vigorous at first, and after a certain depolymerization has been effected, increasing process controls up to an optimum.

The wood preservatives of the present invention include the usual shingle stain wood preserving oils.

By the phrase without substantial reduction when applied to catalyst activity is not meant to include reduction in activity due to age.

Concerning the conversion of the molecular complexes contained in the starting material: the highest boiling fractions of the starting material may be viewed as a multiplicity of rings or molecular complexes. These multiplicity of rings are converted in step-wise fashion to the products of the present invention. By the term step-wise is meant progressively; such progressive conversion, in accordance with the present invention, institutes and maintains without substantial reduction, the depolymerizing hydrogenation of the present invention by the joint action of hydrogen and hydrogen sulfide, in the presence of a sulphide catalyst.

The oils and/or solids also contained in the starting materials, other than said molecular complexes, are also converted to constituency in the products of the present invention.

The sulfide catalysts of the present invention include those catalysts of other forms, converted to sulfides prior to or during the process.

Minor changes may be made in the steps of the process within the scope of the following claims without departing from the spirit of the invention.

5 I claim:

1. In the joint production of solvents and wood preservatives from a mixture of high temperature coal tar fractions boiling not in excess of about 15% at 355° C., the process which comprises: subjecting said material to the action of hydrogen in the presence of a sulfide catalyst with the time so coordinated with a temperature above 400° C. and a pressure selected between the limits of about 200-400 atmospheres as to provide newly formed low boiling solvent fractions having an aromatic content of at least about 50%, said newly formed low boiling solvent fractions boiling below and contiguous to other newly formed fractions of induced toxicity; maintaining a hydrogen sulfide partial pressure by adding sulfur containing material equivalent to about one-half of one percent sulfur; stripping the treated material of low boiling fractions to provide a low boiling solvent having an aromatic content of at least about 50% thereby providing as a residue an oil of the wood preserving type having not more than about 10% boiling below 210° C. nor less than about 45% boiling up to 355° C.

30 2. In the joint production of solvents and wood preservatives from a mixture of high temperature coal tar fractions boiling not in excess of about 15% at 355° C., the process which comprises: subjecting said material to the action of hydrogen in the presence of a sulfide catalyst with the time so coordinated with a temperature above 400° C. and a pressure selected between the limits of about 200-400 atmospheres as to provide newly formed low boiling solvent fractions having an aromatic content of at least about 50%, said newly formed low boiling solvent fractions boiling below and contiguous to other newly formed fractions of induced toxicity; maintaining a hydrogen sulfide partial pressure by adding sulfur containing material equivalent to about one-half of one percent sulfur; stripping the treated material to provide a relatively low boiling solvent having an aromatic content of at least about 50% and a relatively high boiling oil of the wood preserving type boiling not more than about 10% at 210° C. nor less than about 45% at 355° C.

JACQUELINE E. HARVEY, JR.
